MACHINE FOR CUTTING AND WINDING
MATERIALS

Oscar I. Judelshon, New York, N. Y.

Application September 30, 1942, Serial No. 460,200

9 Claims. (Cl. 164—65)

My invention relates to a new and improved machine for cutting and winding materials, such as cloth or the like.

The principal objects of my invention are to improve the type of cutting machine in which the material is passed between a pressure roll and one or more circular knives; to prevent the stretching of the material in the machine, especially if the material is bias-cut woven fabric; to wind the cut material uniformly on a take-up reel or reels in spiral form; to operate the pressure roll and the circular knife or knives at the same linear circumferential speed; to provide a take-up feed roll towards which the take-up reel is urged by gravity; to operate the pressure roll and each associated circular knife at greater linear circumferential speed than the take-up feed roll; to wind no material on the take-up feed roll so that its linear peripheral or circumferential speed remains constant; to cut the material by a shearing action, as distinguished from a pressure action; and to prevent excessive drag on the material which is fed through the machine.

Numerous additional objects of my invention will be stated in the annexed description and drawings, which illustrate a preferred embodiment thereof.

Fig. 1 is a side elevation of the improved machine.

Fig. 2 is a section on the line 2—2 of Fig. 1.

Fig. 3 is a top plan view.

Fig. 4 is a detail perspective view of certain essential parts.

Fig. 5 is a detail view.

The material which is to be cut, which may be cloth or any other material, is wound spirally in the form of a magazine roll C, on a magazine reel or bobbin I. Said reel I has reduced ends, which rest turnably upon opposed pairs of anti-friction rolls 88, which are turnably connected to rigid and stationary arms 89, which are fixed to the frame F of the machine.

The material is led off said spiral magazine roll C, in the form of a flat web W. Said web W is led successively over cylindrical guide-members 5, 6, 7, 8, and 9.

The spaced guides 5 and 8 are connected in respective fixed positions to rigid supporting arms 98 which are fixed to the frame F. The guides 6 and 7 are connected to an arm 96, which is fixed to a shaft 97, which is connected turnably to one of said arms 88. Ratchet wheel 99 is fixed to shaft 97. Said ratchet wheel 99 can thus be turned, in order to adjust guides 6 and

7 in unison, relative to guides 5 and 8. The positions of guides 6 and 7 are adjusted relative to guides 5 and 8, in order to regulate the tension on the web W as it passes over said guides. The ratchet wheel 99 is held releasably in its adjusted position, by pawl 100 which is pivoted to one of the arms 98 at 101. These guides 5, 6, 7 and 8 may be rotatable or non-rotatable about their respective longitudinal axes. They are preferably non-rotatable. Guide 9 is connected in fixed position to the frame F. Said guide 9 is also preferably non-rotatable about its longitudinal axis, although it may be rotatable.

After the guide 9, the web W is led between the pressure roll 10 and the circular cutters or knives 12 and 14. In this embodiment, two knives are used, in order to trim the edges of the web, by cutting off edge strips 18 and 19. I can use any number of such knives, between the longitudinal edges of the web W.

Pressure or backing roll 10 is fixed to a shaft 11, whose ends are turnably supported in bearings of the frame F. This pressure roll 10 has a very smooth non-friction surface.

The knives 12 and 14 are respectively turnably connected to respective bars 25, which pass through respective heads 26, which have U-shaped cross-sections. Said heads 26 are clamped adjustably to shaft 20, in order to make it possible to adjust the lateral distance between said knives 12 and 14, and thus to regulate the widths of the strips 18 and 19 which are cut off adjacent the longitudinal edges of web W. The ends of shaft 20 are turnable in bearings which are provided in the frame F. Bars 25 and the abutting inner walls of heads 26 are shaped so that said bars 25 turn in unison with said heads 26, relative to the axis of rotation of shaft 20. Rods 25 may be fixed to heads 26, after said parts have been adjusted relative to each other, so that said rods 25 cannot shift relative to said heads 26 while the machine is running, or rods 25 may be longitudinally slidable relative to heads 26, while the machine is running.

The bars 25 and the heads 26 are shaped so that the only movement between said heads 26 and said bars 25, is a longitudinal movement of said bars 25 in the direction of their parallel longitudinal axes. The pressure roll 10 positively turns the knives 12 and 14 by friction, without any relative slip, or with any desired relative slip.

A plate 27 is fixed to the outer end of each bar 25. The plates 27 may be rigid or resilient. An eye-bolt 28 is fixed to each plate 27. The upper end of a tension spring 29 is fixed to each

eye-bolt 28. The lower end of each said tension spring 29 is fixed to a lower eye-bolt 30. Said lower eye-bolts 30 are fixed to the respective collars or heads 31 of a rod 32, and said heads 31 are fixed by rigid cross-rods to the collars or heads 33 of a rod 34, whose ends are supported in the frame F. Said heads 33 are turnable relative to rod 34, or they may be fixed to rod 34, in which case the rod 34 is turnable about its longitudinal axis. It is preferred to have the heads 33 fixed to rod 34 and to have rod 34 turnable about its longitudinal axis. A bar 34b is fixed to one of said heads or collars 33. A pin 35 can be passed through a hole in the upper end of said rigid bar 34b, and through a selected hole 36 of a stationary perforated member 37, which is fixed to the frame F of the machine. It is thus possible to regulate the tension of springs 29, and hence the pressure of knives 12 and 14 against pressure roll 10. Said pressure may be sufficient to cause roll 10 to drive the knives 12 and 14 frictionally, in unison with roll 10, and without any relative slip. By turning bar 34b clockwise from the position of Fig. 4, such tension of springs 29 and such pressure of knives 12 and 14 against roll 10 are increased. By turning said bar 34b counterclockwise, namely, in the direction of arrow 34a, the tension of springs 29 is decreased. A stop bar 38 is located within each helical tension spring 29, in order to limit the minimum distance between eye-bolts 30 and 28 and the minimum tension of springs 29.

After the cutting operation, the web W is led around a part of the periphery of a turnable knurled take-up feed roll 15, whose shaft-ends 16 are turnably supporting in bearings of the frame F of the machine.

The cloth is then wound-up in spiral form on the hollow take-up reel 17 which is releasably fixed to the shaft 17a.

The machine has a motor 39, whose shaft is connected by belt 41 to pulley 42, which is fixed to shaft 43, which passes through the turnable sleeve 46. The usual grooved shift-collar 44, which has the usual forked hand-operated shifter 47, is keyed by key 43a to a groove of shaft 43. Said grooved collar 44 is slideable on shaft 43, in the usual manner. Collar 45 is fixed to sleeve 46. The collars 44 and 45 respectively have the usual clutch tooth and clutch recess, so that shaft 43 can be coupled to or uncoupled from sleeve 46. The usual friction clutch can be used instead of the toothed clutch disclosed herein.

Sprocket 48, which is fixed to sleeve 46, is connected by chain 49 to sprocket 50, which is rotated on stud shaft 51. Said sprocket 50 is fixed to sprocket 52 and to gear 70, so that said elements 50, 52 and 70 turn in unison on stud shaft 51.

Gear 70 meshes with the larger gear 71 which is fixed to shaft 11, so as to positively drive the backing or pressure roll 10.

Sprockets 75, which is fixed to shaft 11, is connected by chain 76 to sprocket 77, which is fixed to sprocket 79. Sprockets 77 and 79 are mounted on and they can turn freely relative to stud shaft 78. Sprocket 79 is connected by chain 81 to sprocket 80, in order to drive shaft 4 in unison with the knurled feed rolls 3, in order to positively turn the magazine roll of material C at its periphery by the frictional drive of said feed rolls 3, thus preventing undesirable tension. Shaft 4 is mounted in bearings of arms 82, whose ends 82a are turnably mounted on suitable aligned pivot members. One of these pivot members is the stud

shaft 78, on which the respective end 82a can turn freely. The weight of said arms 82 and of the parts mounted thereon is sufficient to provide the frictional drive between the periphery of the feed rolls 3 and the roll of material C.

Sprocket 72, which is fixed to shaft 11, drives the larger sprocket 74 by means of chain 75. Said sprocket 74 is fixed to shaft 16 of the take-up feed roll 15. As an example, and without limiting the invention thereto, the diameter of pressure roll 10 may be 4.25 inches, and the diameter of take-up feed roll 15 may be 4.00 inches, and the pitch diameter of sprocket 74 is approximately 106% of the pitch diameter of sprocket 72. Hence the linear peripheral velocity of roll 15 is less than that of roll 10. Roll 15 has a smaller angular velocity than roll 10.

As previously stated, sprocket 52 is fixed to sprocket 50, so that sprockets 52 and 50 turn in unison on stud shaft 51. Sprocket 52 is connected by chain 54 to sprocket 55, which turns freely on stud shaft 53. Sprocket 56, which is fixed to sprocket 55, is connected by chain 57a to sprocket 57, whose hub 57b is fixed to friction disc 95. Said hub 57b and said driving friction disc 95 can turn freely relatively to shaft 17a, when driven friction disc 93 is uncoupled from friction disc 95. Friction disc 93 has hub 92. Hub 92 has key-pin 94 which is slideable in a longitudinal recess of shaft 17a, so that friction disc 93 and shaft 17a turn in unison. Collar 90 is fixed to shaft 17a. Compression spring 91 biases driven friction disc 93 to coupling position relative to driving friction disc 95.

The shaft 17a has bearings in two arms 58, which are pivotally mounted on stud shaft 53.

Each of said arms 58 is pivotally connected at 59 to a link 60, which is pivotally connected at 61 to a lever 62, which is pivoted at 63 to frame F. Each lever 62 has the adjustable counter-weight 64, and additional counterweights 66 can be supported on respective heads 67 of respective rods 65, whose respective upper ends are pivotally connected to the respective levers 62. Each arm 58 is thus provided with a link 60 and a lever 62 and the associated parts which are shown in Fig. 1.

The operation of the machine is as follows:

Before starting the machine, the operator pulls the end of the web W off magazine roll C. The end of the web is led around parts of the guides 5, 6, 7, 8 and 9, and between the pressure roll 10 and the circular knives 12 and 14. To facilitate the insertion of the web between pressure roll 10 and said knives, the bar 34 can be then adjusted so that springs 29 have little or no tension. Said knives can be moved out of contact with pressure roll 10, in order to facilitate the insertion of the web between said knives and said pressure roll 10. The web is then led around a part of the take-up roll 15, and the end of the web is connected to the take-up reel 17 on shaft 17a. Said reel 17 can be removed from shaft 17a by a relative sliding movement in the well-known manner. Reel 17 is releasably fixed to shaft 17a.

The counterweights 66 and 64 turn each lever 62 so as to push each link 60 upwardly, thus biasing the shaft 17a away from the take-up roll 15, by urging the arms 58 to turn upwardly around the axis of stud shaft 53. This biasing is controlled by the number of weights 66 which are utilized. As the material is accumulated upon the take-up reel 17, more counterweights 66 can be added.

The motor 39 is then started, and the clutch

members 44 and 45 are coupled, so that shaft 43, which is driven by pulley 42, will drive sleeve 46 and its sprocket 48. Chain 49 will rotate sprocket 50 on stud shaft 51, thus driving gear 70 and sprocket 52.

Gear 70 will turn the larger gear 71, so that the angular velocity of shaft 11 and the angular velocity of its backing of pressure roll 10 will be less than the angular velocity of shaft 43.

Sprocket 72 will drive sprocket 74, thus turning the take-up feed roll 15 at slightly lower linear peripheral velocity than the linear peripheral velocity of pressure roll 10 and the linear peripheral velocity of the knives. This difference in linear peripheral velocity between rolls 15 and 10 depends on the kind of material which is being cut. Said difference may be very slight. Said difference is regulated by selecting the difference in pitch diameter of sprockets 72 and 74, or by selecting rolls 15 and 10 of suitably different outer diameters.

Sprocket 75 will drive sprocket 77, thus driving sprocket 79 and sprocket 80 and shaft 4. The knurled friction rolls 3 will thus positively drive the magazine roll C at its periphery, so that said roll is driven in order to unwind the material therefrom. This positive drive of roll C is selected to prevent excessive tension on the web W of said material, anterior said roll C. The drawings are substantially to scale and reference is made thereto for further details. As the material is unwound from roll C, the arms 82 will turn downwardly by gravity around the axis of the stationary stud-shaft 78, so that the rolls 3 will always maintain their friction drive. This positive friction drive is sufficient at all times to prevent excessive tension upon and undesirable stretching of the web W.

The speed at which the material is unwound from the magazine roll C, and at which the material is fed through the machine, is fixed wholly by the linear peripheral speed of the take-up feed roll 15. This feeding speed is a constant speed, because no material is ever wound upon said take-up feed roll 15. The weight of arms 58 and of shaft 17a and of take-up reel 17 is always sufficient to produce a frictional drive between take-up feed roll 15 and the material Ca which is wound upon said reel 17. One of the features of my invention is that the drive of feed-roll 15 omits a slip-friction drive, so that said feed-roll 15 is always driven in fixed relation to the cutting means. Hence the tension on the fabric is maintained uniform, between the roll of wound-up material and the cutting means.

Since the pressure roll 10 always has a greater linear peripheral speed than the linear peripheral speed of the take-up feed roll 15, said pressure roll 10 always has a greater linear peripheral speed than the linear speed of the web W. Hence the pressure roll 10, which has a very smooth surface, will always slip slightly relative to the web, so that the cutting action is always a shearing action, instead of being a mere pressure action. The circular knives 12 and 14 are always frictionally driven by the pressure roll 10, so that said knives have a greater peripheral linear speed than the speed of the web, thus producing the desired shearing cutting action. As shown in Fig. 4, the cutting portions of the knives move in the same direction as the web. The guides 5, 6, 7, 8 provide an adjustable drag upon the movement of the web, anterior the cutting zone, so that the web W is under regulated

tension between guides and the take-up feed roll 15, and hence at the knives.

As the trimmed material is accumulated upon the take-up reel 17, the shaft 17a will rise. Fig. 1 shows one position of shaft 17a in full lines, and it shows a higher position of said shaft 17a in broken lines.

The trimmed-off edge strips 18 and 19 are led out of the machine by pairs of feed rolls 21 and 23 which are fixed to shafts 22 and 24.

5 The shaft 22 is turnably mounted in arms 85, which are fixed to frame F by bolts 86. Shaft 22 has a pulley 83, which is driven by belt 84, part of which is located in a groove of the pressure roll 10, which therefore acts as a drive pulley. Shaft 24 is mounted in arms 86, which are pivoted at 87 to frame F, so that a friction feed is provided between the feed rolls 21 and 23.

10 The slip of the friction clutch 93-95 is sufficient to keep the material Ca on the reel 17 under suitable tension, so as to wind up the material in the form of a uniformly tight roll. The slip of the friction drive can be regulated by selecting a suitable control spring 91. The force with which the spring 91 produces the slip friction drive can be varied for different materials. The object is to produce a tight wound-up roll without objectionably stretching the cloth or other material.

15 The knurled rolls 3 and the take-up roll 15 may have equal outer diameters.

20 The slip-friction drive 95-93 always urges the periphery of the take-up reel 17 to turn at greater linear peripheral velocity than the linear peripheral velocity of the take-up roll 15, so that the material is wound up under tension to produce the roll Ca.

25 If additional knives are located between the knives 12 and 14, the web is cut into strips of any desired width.

30 I have described a preferred embodiment of the invention, but it is clear that numerous changes and omissions can be made without departing from its spirit.

35 For example, while I have disclosed a complete machine, the invention includes numerous valuable sub-combinations, which can be used independently of said complete machine, or in other machines of many different types.

40 The member 15 is generically described as feeding means for feeding the web through the machine at constant predetermined speed. When I refer to circular cutting means, I include a single circular knife or any number of circular knives. 45 Likewise, when I specify driving means in a claim or claims, I include the use of a single master motor or the use of a plurality of motors.

I claim:

46 1. In a cutting machine for cutting a web, feeding means adapted to move said web through the machine at constant predetermined speed, a pressure roll and circular cutting means located anterior said feeding means, said circular cutting means being frictionally driven by said pressure roll, biasing means for biasing said circular cutting means towards said pressure roll in order to cut the web between said pressure roll and said circular cutting means, driving means adapted to operate said feeding means at constant predetermined speed and to revolve said pressure roll at a linear peripheral speed which exceeds said predetermined speed.

51 2. In a cutting machine for cutting a web, feeding means adapted to move said web through the machine at constant predetermined speed, a

pressure roll and circular cutting means located anterior said feeding means, said circular cutting means being frictionally driven by said pressure roll, biasing means for biasing said circular cutting means towards said pressure roll in order to cut the web between said pressure roll and said circular cutting means, driving means adapted to operate said feeding means at constant predetermined speed and to revolve said pressure roll at a linear peripheral speed which exceeds said predetermined speed, and means for subjecting the web to a drag anterior said pressure roll.

3. In a cutting machine, a pressure roll, a disc knife, a holding rod to which the disc knife is turnably connected, a turnable shaft, connecting means connecting said holding rod to said shaft intermediate the ends of said holding rod so that said holding rod is turnable around the axis of said shaft, a second shaft, an adjustment rod laterally spaced from said second shaft and fixed to said second shaft, a tension spring whose ends are respectively connected to said holding rod and to said adjustment rod, means for turning said second shaft to adjusted position and for holding said second shaft in its adjusted position.

4. In a cutting machine, circular cutting means, feeding means adapted to feed a web of material through said machine at constant speed, a pressure roll, said circular cutting means being frictionally driven by said pressure roll, drive means for driving said pressure roll and said circular cutting means at a peripheral speed which is greater than said constant speed.

5. In a cutting machine, feeding means adapted to feed a web of material through said machine at constant speed, a pressure roll, circular cutting means frictionally driven by said pressure roll, drive means for driving said pressure roll and said circular cutting means at a peripheral speed which is greater than said constant speed, and means located anterior said circular cutting means and adapted to subject the web to tension anterior said circular cutting means.

6. A cutting and winding machine comprising a support for turnably supporting a magazine reel, a pressure roll, circular cutting means associated with said pressure roll, biasing means which bias said circular cutting means towards said pressure roll, tension-producing means which produces a tension on the web anterior said pressure roll, said tension-producing means being located intermediate said pressure roll and said magazine reel, a take-up feed roll, said pressure roll and the associated circular cutting means being located intermediate said tension-producing means and said take-up feed roll, a take-up reel which is movable towards and away from said take-up feed roll, said take-up reel being biased towards said take-up feed roll, so that the material which is wound upon said take-up reel contacts with the periphery of said feed roll under said biasing force, supplemental feed rolls which are biased towards said magazine reel so that said supplemental feed rolls contact with the material which is wound upon said magazine reel, means for rotating the take-up reel, said

means for rotating the take-up reel including slip-friction means, driving means for driving said take-up feed roll at constant linear peripheral speed and for driving said pressure roll and the associated circular cutting means at greater linear peripheral speed and for revolving said supplemental feed rolls and for actuating said means for turning the take-up reel.

7. In a cutting machine for cutting a web, feeding means for feeding the web through the machine at constant predetermined speed, tensioning means for tensioning the web, said tensioning means being located anterior said feeding means, circular cutting means located intermediate said feeding means and said tensioning means, non-slip drive means which operate said feed-means and which rotate said circular cutting means, said drive means turning said circular cutting means at greater peripheral cutting speed than and in fixed non-slip proportion to said constant predetermined speed of the web, said feeding means being the only means for determining the speed of the web through the machine.

8. In a cutting machine for cutting a web, a take-up reel on which the cut web is wound up in the form of a spiral roll, a friction feed roll located to contact with the periphery of said spiral roll, said take-up reel being mounted movably relative to said friction feed roll so that the spacing between said take-up reel and said friction feed roll is increased as the diameter of said spiral roll is increased, said friction feed roll being the only means for determining the speed of the web through the machine, tensioning means for tensioning the web, said tensioning means being located anterior said take-up reel and said feed roll, circular cutting means located intermediate said feed roll and said tensioning means, non-slip drive means which rotate said feed roll at constant speed and which also rotate said circular cutting means so that the peripheral speed of said cutting means is greater than and in fixed non-slip proportion to the peripheral speed of said feed roll.

9. In a cutting machine for cutting a web, a take-up reel on which the cut web is wound up in the form of a spiral roll, a friction feed roll located to contact with the periphery of said spiral roll, said take-up reel being mounted movably relative to said friction feed roll so that the spacing between said take-up reel and said friction feed roll is increased as the diameter of said spiral roll is increased, said friction feed roll being the only means for determining the speed of the web through the machine, tensioning means for tensioning the web, said tensioning means being located anterior said take-up reel and said feed roll, circular cutting means located intermediate said feed roll and said tensioning means, non-slip drive means which rotate said feed roll at constant speed and which also rotate said circular cutting means so that the peripheral speed of said cutting means is greater than and in fixed non-slip proportion to the peripheral speed of said feed roll, said machine also having slip-friction drive means for rotating said take-up reel in order to wind said spiral roll under tension on said take-up reel.

OSCAR I. JUDELSHON.
